UNITED STATES PATENT OFFICE

JOHN W. ASHWORTH, OF NEW YORK, N. Y., ASSIGNOR TO ASHWORTH ADVERTISING COMPANY, INCORPORATED, OF NEW YORK, N. Y., A CORPORATION OF NEW YORK

REPEATING APPARATUS FOR PHONOGRAFS

Application filed April 8, 1929. Serial No. 353,611.

This invention relates to repeating apparatus adapted to be associated with phonograph instruments whereby the playing or reproduction of a record may be repeated over and over again without appreciable intervening periods of cessation and for any number of times, the construction being such as to repeat the reproduction until the mechanism is manually stopped.

Devices have heretofore been suggested to effect the repetition of the reproduction of records on phonographs. Such prior devices have, however, generally been in the form of attachments or accessories adapted to be mounted and clamped in place on the top of the phonograph cabinet directly adjacent the turntable and for various reasons well known to the art, have not proven satisfactory.

The present invention, in contradistinction, is preferably built into the phonograph construction to form a permanent part thereof and to be always ready and able to carry out its inherent functions in a thoroughly efficient and positive manner.

The invention is susceptible to employment with phonographs employing either any well known type of sound reproducer or sound box, as well as those types of magnetic pick up now in vogue for translating the vibratory operations of the stylus under the impulse of the sound groove of a record into electrical vibrations which are impressed upon radio apparatus and amplified and reproduced thereby.

Speaking generally, the invention consists in an arm or lever mounted for pivotal movement so as to function preferably as a first class lever. The lever is so configured that the work arm thereof is adapted for cooperation with the tone arm or equivalent part of the phonograph. While the power arm of such lever is shaped to carry a cam follower associated with the cam which acts to control the operations of said lever in order that such lever may act upon the tone arm to bring about movement of the latter from the position wherein the stylus completes the travel of the sound groove of the

record back to a new start at the beginning of such sound groove.

I find it highly practical to so form the work arm of the lever that it will project below and underlie the tone arm in a plane substantially parallel to the plane of the face of the record, so that as the tone arm swings during the travel of the stylus in the sound groove of the record, said tone arm will move substantially free from contact with the work arm of the lever. As the stylus approaches the end of the sound groove, however, the cam which is operated in accordance with this invention by one of the operating parts of the phonograph, will act upon the cam follower to permit pivotal movement of the lever thereby causing the work arm of the latter to swing sharply upward and partake of a pronounced inclined position. During the upward movement of such power arm, the tone arm will be engaged and lifted and will thereupon gravitate down the inclined power arm of the lever until it engages a stop regulatably mounted on the power arm in such position as to bring the stylus to rest in substantially juxtaposition with the beginning of the sound groove. Continued operation of the cam will return the lever to its normal position, thereby carefully replacing the stylus in the beginning of the sound groove of the record without shock or vibration.

The invention further includes mechanism adapting the device to function with records of different sizes as will hereinafter be more fully explained.

Another feature of the invention resides in the manner, hereinafter more fully explained, of driving the repeating apparatus and the turntable of the phonograph with which it is associated.

Features of the invention, other than those adverted to, will be apparent from the hereinafter detailed description and claims, when read in conjunction with the accompanying drawings.

The accompanying drawings illustrate one practical embodiment of the invention, but the construction therein shown is to be under-

stood as illustrative, only, and not as defining the limits of the invention.

Figure 1 is a plan view of a phonograph instrument embodying the present invention.

Figure 2 is a section on the line 2—2 of Figure 1.

Figure 3 is a side view of a novel form of stylus also constituting a part of this invention.

Figure 4 is a section on the line 4—4 of Figure 3.

In the accompanying drawings, 1 designates a casing of a phonograph which may, in practice, be made in any desired form of cabinet and constructed of any suitable material, the particular form of cabinet being immaterial to this invention. 2 designates the turntable of the phonograph and on which turntable a record 3 is adapted to be supported in the usual manner.

The turntable is fixed to a spindle 4 journaled for rotation on a vertical axis in any suitable manner and to the lower end of the spindle is secured a pulley 5 having a belt connection 6 with a pulley 7 fixed to the armature shaft of a motor 8. It will of course be understood that instead of the electric motor 8 as shown in the drawings, a suitable spring motor such as heretofore used in phonographs may be employed. An appropriate ball governor 9 is associated with the motor 8 in order to control and regulate the speed at which the turntable is rotated.

I wish to call attention at this point to the novel form of belt drive which I have disclosed. The driving of the turntable through a belt connection as shown gives an unusually flexible drive wherein there is a notable absence of noise and nevertheless the turntable is rotated with a smoothness of motion in marked contradistinction to the gear or worm drives heretofore generally employed.

The tone arm 10 is supported on the cabinet in any suitable manner for swinging movement in a direction substantially radially of the record and also for lifting pivotal movement with respect to the record and with the tone arm is associated a suitable horn 11 of any appropriate character. 12 designates the sound box of the phonograph, although such sound box may be replaced by one of the so-called magnetic pick up, the purpose of which is to permit of undulatory or lateral deviations in the sound groove to be translated into corresponding changes in electrical current for reproduction through a radio instrument in the well known manner. Thus, the present invention may be employed in phonographs intended to be used in the conventional manner or with such phonographs when associated with a radio set for reproduction.

Mounted in any suitable manner within the cabinet 1 is a frame 14 which carries in a compact and convenient manner the

greater portion of the mechanism incident to reproduction of the records. This mechanism will now be described.

Journalled for rotation in the frame 14 are two alined shafts 15 and 16 and two other alined shafts 17 and 18, the latter two of which are parallel to the former two. The shaft 15 has affixed to one end thereof a gear 19 which meshes with another gear or worm 20 on the spindle 4. The connection 19 and 20 may be a worm and gear connection or a substantially 45 degree gear connection. In either event, the purpose of such connection is to drive the shaft 15 from the spindle 4 in order to obtain a perfectly timed and synchronously operable rotation of the shaft 15 with respect to the record. The shaft 15 carries a gear 21 meshing with the gear 22 on the shaft 17 while the shaft 16 carries a gear 23 meshing with a gear 24 on the shaft 18. The alined shafts 15 and 16 are adapted to be connected by a sliding clutch sleeve 25 and the shafts 17 and 18 are adapted to be connected by a similar sliding clutch sleeve 26. These two clutch sleeves are splined to the shafts 15 and 17 and are adapted to engage with adjacent polygonal ends of the shafts 16 and 18. The two sleeves are connected together by means of a clutch lever 27 secured intermediate its ends to a pivot rod 28 which extends to the exterior of the cabinet and is provided with a knob 29, so that by turning the knob in one direction or the other either pair of alined shafts may be connected together to the exclusion of the other pair. The gear ratios are such that when the shafts 15 and 16 connected for a direct drive, the structure will be operative to properly function with a standard large size record, whereas when the shafts 17 and 18 are connected, the speed of the shaft 16 will be increased to render the device appropriate for use with the small size standard record. The apparatus is thus adapted to cooperate with both standard sizes of record and may be regulated for this purpose by merely turning the knob 29 in an appropriate direction.

To the shaft 16 is secured a bevel gear 30 which meshes with the bevel gear 31 secured to a shaft 32 which also carries a cam 33. The upper face of this cam is flat for the greater portion of its circumference, but at one point in its circumference it is cut away to provide a low phase designated 34 in Fig. 2. With the cam surface is adapted to cooperate a follower 35 mounted on the power arm 36 of a lever fulcrumed at 37 and having a power arm 38. A spring 39 serves to hold the follower in contact with the cam. The lever is so shaped that its work arm extends substantially radially of the record in a position to overlie the record and underlie the tone arm 10. Under normal conditions, the lever occupies the full line position of Figure 2, where it is free from both the record and the

tone arm. In this position, the follower 35 is riding on the flat face of the cam and the stylus is traversing the sound groove of the record. The parts are so geared together 5 that at the time the stylus finishes its travel at the inner end of the sound groove, the cam 33 will have rotated to a position wherein the follower will drop to the low phase 34 of the cam under the impulse of the spring 39. 10 This will cause the lever to be tilted into the dotted line position whereby the work arm 38 will engage with the tone arm and lift the stylus free from the record.

At the same time, the work arm 38 will be 15 in a marked inclined position and as a result gravity will act upon the tone arm to cause it to slide down the incline until it engages with a stop 40 adjustably secured on the work arm of the lever.

20 When the tone arm engages with this stop, the tone arm comes to rest and as the machine continues to operate and the cam 33 rotate, the follower will slowly be elevated by the inclined portion 41 of the cam in 25 order to return the lever to the full line position shown in Fig. 2, and during this operation, the stylus will be quietly and slowly lowered to present the stylus without shock or jar at the beginning of the sound groove. 30 It will be noted in this regard that the stop 40 will be regulated manually in accordance with the size of the record to be played, so that when the tone arm is lowered, the stylus will be presented at the beginning of the 35 sound groove.

The structure which I have described is 40 unusually simple from a mechanical standpoint, is absolutely unfailing in its operation, and its use in practice has demonstrated its unquestionable efficiency in the performance of its intended functions.

I find it desirable to associate with the apparatus a tone arm support designated generally by the reference character 45. This 45 support is preferably made in the form of a resilient wire suitably anchored to the tone arm mounting fixture 46 and extending so as to underlie the tone arm and bent as indicated at 47 to grip the outer end of the tone arm directly adjacent the sound box. This wire is so tensioned that when the stylus is traversing the record an appreciable portion of the weight of the tone arm will be carried by the support 45, so as to take undue weight 50 of the tone arm and sound box off the stylus. However, when the tone arm is lifted at the end of the sound groove, so as to permit it to slide down the inclined work arm of the lever, the spring support 45 will be flexed in an upward direction and will assist gravity in causing the tone arm to expeditiously slide down the work arm to the point of beginning 55 of the sound groove.

Any suitable form of stylus may be employed, but in Figures 3 and 4, I have illus-

trated a novel stylus construction which may be used with any form of record and is practically indestructible. The stylus shown comprises a holder 41 bifurcated to receive between the legs thereof a knife edge disk 42 70 held firmly in position by means of a set screw 43 which clamps the legs together. It is not intended that the disk should rotate, although it may without departing from this invention. If clamped tightly in place, 75 it may be manually rotated from time to time to compensate for wear at any particular point. The shank 44 is adapted to be received into the conventional stylus holder and held in place therein in any suitable 80 manner.

The foregoing detailed description sets forth the invention in its preferred practical form, but the invention is to be understood as fully commensurate with its appended 85 claims.

Having thus fully described the invention, what I claim as new and desire to secure by Letters Patent is:

1. In a phonograph, a driven spindle, a 90 turntable mounted on the spindle, a tone arm, and a sound box carrying a stylus and supported on the tone arm, in combination with a lever having work and power arms and fulcrumed for pivotal movement with the 95 work arm underlying the tone arm and the power arm having a cam follower, a cam cooperating with said follower, positive driving connections between the cam and the spindle to continuously drive the former 100 from the latter, said cam being shaped to maintain the work arm of the lever free from engagement with the tone arm while the stylus is traversing the sound groove of the record and to move said work arm of the 105 lever into inclined position when the stylus completes its travel of the sound groove whereby the stylus is lifted from the record and the tone arm caused to slide down the work arm, and means for stopping the tone 110 arm with the stylus in juxtaposition with the beginning of the sound groove.

2. In a phonograph, a driven spindle, a turntable mounted on the spindle and operable thereby, a tone arm, and a sound box 115 carrying a stylus supported on the tone arm and adapted for cooperation with the record supported on the turntable, in combination with a lever having work and power arms and fulcrumed for pivotal movement with the work arm underlying the tone arm and the power arm having a cam follower, a cam 120 cooperating with said follower, driving connections between the cam and the spindle, said cam being shaped to maintain the work arm of the lever free from engagement with the tone arm while the stylus is traversing the sound groove of the record and to move said work arm of the lever into inclined position 125 when the stylus completes its travel of the 130

- sound groove for the purpose of lifting the stylus from the record to permit the tone arm to slide down the work arm, and means for stopping the tone arm with the stylus in juxtaposition with the beginning of the sound groove, said stop means comprising an adjustable stop adapted to be regulated to positions appropriate to records of different sizes.
- 10 3. In a phonograph a driven spindle, a turntable mounted on the spindle, a tone arm, and a sound box carrying a stylus and supported on the tone arm, in combination with a lever having work and power arms and fulcrumed for pivotal movement with the work arm underlying the tone arm and the power arm having a cam follower, a cam co-operating with said follower, positive driving connections between the cam and the spindle to continuously drive the former from the latter, said cam being shaped to maintain the work arm of the lever free from engagement with the tone arm while the stylus is traversing the sound groove of the record and to move said work arm of the lever into inclined position when the stylus completes its travel of the sound groove, whereby the stylus is lifted from the record and the tone arm caused to slide down the work arm, and means for stopping the tone arm with the stylus in juxtaposition with the beginning of the sound groove, said stop means comprising an adjustable stop adapted to be regulated to positions appropriate to records of different sizes.
- 15 30 35 40 45 50 55 60 65 70 75 80 85 90 95 100 105 110 115 120 125 130
3. In a phonograph, a driven spindle, a turntable mounted on the spindle, a tone arm, and a sound box carrying a stylus and supported on the tone arm, in combination with record repeating means embodying a driving shaft positively connected to and constantly driven by the spindle of the turntable, a cam, a driven shaft operatively connected to the cam, alined counter shafts geared to the respective shafts, clutch elements for connecting the driving and driven shafts directly or through the counter shafts depending upon the positions of the clutch elements, a lever of the first class having power and work arms, the power arm of which is adapted to cooperate with the cam and the work arm of which is adapted to underlie the tone arm, said cam being shaped to normally maintain the work arm of the lever free from engagement with the tone arm and said cam being shaped to cause movement of the lever into a position wherein its work arm will be inclined and will lift the tone arm to disengage the stylus from the record at the end of the sound groove and permit the tone arm to gravitate into a position wherein the stylus will be juxtaposed with the beginning of the sound groove, and an adjustable stop carried by the work arm of the lever to control the position at which the stylus is placed at the end of the sliding movement of the tone arm on the work arm of the lever, and a resilient tone arm supporting element having a neutral position between the raised and lowered positions of the tone arm, said supporting element being connected to the tone arm to partially support the weight of the tone arm when the stylus is engaged with the sound groove and to assist gravity in causing the tone arm to slide down the work arm of the lever when the tone arm is elevated by said lever.
4. In a phonograph, a driven spindle, a turntable mounted on the spindle and operable thereby, a tone arm, and a sound box carrying a stylus supported on the tone arm and adapted for cooperation with the record supported on the turntable, in combination with record repeating means embodying a driving shaft positively connected to and driven by the spindle of the turntable, a cam, a driven shaft operatively connected to the cam, alined counter shafts geared to the respective cams, clutch elements for connecting the driving and driven shafts directly or through the counter shafts depending upon the positions of the clutch elements, a lever

of the first class having power and work arms, the power arm of which is adapted to cooperate with the cam and the work arm of which is adapted to underlie the tone arm, said cam being shaped to normally maintain the work arm of the lever free from engagement with the tone arm and said cam being shaped to cause movement of the lever into a position wherein its work arm will be inclined and will lift the tone arm to disengage the stylus from the record at the end of the sound groove and permit the tone arm to gravitate into a position wherein the stylus will be juxtaposed with the beginning of the sound groove, an adjustable stop carried by the work arm of the lever to control the position at which the stylus is placed at the end of the sliding movement of the tone arm on the work arm of the lever, a motor, and belt and pulley connections between the motor and the spindle.

7. In a phonograph, a driven spindle, a turntable mounted on the spindle and operable thereby, a tone arm, and a sound box carrying a stylus supported on the tone arm and adapted for cooperation with the record supported on the turntable, in combination with record repeating means embodying a driving shaft positively connected to and driven by the spindle of the turntable, a cam, a driven shaft operatively connected to the cam, alined counter shafts geared to the respective cams, clutch elements for connecting the driving and driven shafts directly or through the counter shafts depending upon the positions of the clutch elements, a lever of the first class having power and work arms, the power arm of which is adapted to cooperate with the cam and the work arm of which is adapted to underlie the tone arm, said cam being shaped to normally maintain the work arm of the lever free from engagement with the tone arm and said cam being shaped to cause movement of the lever into a position wherein its work arm will be inclined and will lift the tone arm to disengage the stylus from the record at the end of the sound groove and permit the tone arm to gravitate into a position wherein the stylus will be juxtaposed with the begining of the sound groove, an adjustable stop carried by the work arm of the lever to control the position at which the stylus is placed at the end of the sliding movement of the tone arm on the work arm of the lever, a motor, belt and pulley connections between the motor and the spindle, said connections comprising a relatively large pulley on the spindle, and a relatively small pulley on the motor with a belt encircling both pulleys.

In testimony whereof I have signed the foregoing specification.

JOHN W. ASHWORTH.
